CLAIM

The ornamental design for a room air conditioner grill, as shown and described.

DESCRIPTION

FIG. 1 is an upper perspective view of a room air conditioner grill showing our new design;

FIG. 2 is an enlarged front elevation view thereof;

FIG. 3 is an enlarged rear elevation view thereof;

FIG. 4 is an enlarged left side elevation view thereof;

FIG. 5 is an enlarged right side elevation view thereof;

FIG. 6 is an enlarged top plan view thereof;

FIG. 7 is an enlarged bottom plan view thereof; and FIG. 8 is a front elevation view of a room air conditioner grill showing a second embodiment of our new design, wherein the sole difference resides in the height of the grill being of indeterminate length, as indicated by being broken away in the middle.

The broken line showing of a room air conditioner body in FIG. 1 is for illustrative purposes only, and forms no part of the claimed design.
